UNITED STATES PATENT OFFICE.

HARRY ANDREW SELLERS, OF ROXBURY, MASSACHUSETTS.

NURSING NIPPLE.

Application filed January 13, 1921. Serial No. 436,898.

To all whom it may concern:

Be it known that I, HARRY A. SELLERS, a citizen of the United States, and resident of Roxbury, county of Suffolk, State of Massachusetts, have invented an Improvement in Nursing Nipples, of which the following description, in connection with the accompanying drawing, is a specification, like characters on the drawing representing like parts.

This invention relates to nursing nipples and it has for its general object to provide a nursing nipple which will not collapse while being used and which is non-leakable, so that if the nursing bottle with the nipple thereon, is laid down on its side without being used, the contents of the bottle will not leak out through the nipple.

In order to give an understanding of my invention I have illustrated in the drawings a selected embodiment thereof, which will now be described after which the novel features will be pointed out in the appended claims.

Fig. 1 is a vertical sectional view through a nursing bottle having my improved nipple applied thereto.

Fig. 2 is a section on the line 2—2, Fig. 1.

Fig. 3 is a sectional view through the nipple removed from the bottle and taken on the line 3—3, Fig. 2.

1 indicates the nursing bottle which may have any suitable or usual construction and which is provided at its upper end with the bead 2, to which the nipple is attached, all as usual. My improved nipple is indicated at 3 and it is formed with the enlarged end 4 which is adapted to be placed over the bead 2 of the bottle as usual.

In order to provide a non-leaking nipple, I construct my improved nipple with a valve which is arranged to normally close the opening 5 in the neck of the bottle, but which will open automatically to allow the milk to be taken from the bottle whenever the nipple is used. This valve is shown at 6 and it is in the form of a plate or clapper which is secured to the nipple at one side and is of sufficient proportion to cover the opening 5 in the neck of the bottle. This valve may be made of any suitable material, but I will preferably use a resilient sheet material, such for instance, as rubber sheeting. The valve member is provided with

a stem 7 which is secured to the wall of 50 the nipple at the enlarged portion 4, so that the valve is permanently attached to the nipple. The stem 7 can be secured to the nipple either by cementing it thereto or in any other suitable way. The construction 60 is such that when the nipple is placed on the bottle, as shown in Fig. 1, the valve 6 will lie against the top of the bottle neck and thus act as a valve to close the neck of the bottle. The resiliency of the valve 6, however, permits it to open away from the bottle neck as shown in dotted lines, Fig. 1 whenever a suction is created in the nipple. Therefore whenever the nursing nipple is being used the milk or other contents of the 70 bottle can flow freely through the neck 5 into the nipple, but as soon as the suction on the nipple ceases, then the valve automatically closes the bottle neck. With this construction it is possible to lay the bottle 75 down on its side without danger that the contents thereof will leak out through the nipple.

The stem 7 not only provides means for attaching the valve to the nipple but it also 80 functions as a vent producing element. Where the stem is secured to the inside of the nipple, as herein shown, then when the nipple is applied to the bead 2 of the bottle, the rubber of the nipple will be held away 85 from the bottle by the stem 7 at the point where the stem is attached to the nipple and this provides an air vent 8, on each side of the stem 7 through which air is admitted to the nipple. This makes the nipple a 90 non-collapsible one.

I claim:

1. The combination with a bottle, of a nipple attached thereto, and a valve secured to the nipple and normally resting against 95 the end of the bottle neck thereby to close the same, said valve being movable bodily away from the end of said neck when suction is produced in the nipple.

2. The combination with a bottle, of a 100 nipple applied thereto, a valve having a hinged connection to one side of the nipple and adapted to close the neck of the bottle.

3. In a nursing nipple, the combination with a nipple body adapted to be applied to 105 the neck of a bottle, of a flap valve of resilient material having a hinged connection with one side of the nipple, and adapted

to close the neck of the bottle when the nipple is applied to the bottle.

4. The combination with a bottle, of a nipple applied to the neck thereof, a flap 5 valve of resilient material having a stem which is secured to the inner wall of that portion of the nipple which embraces the

bead at the neck of the bottle, said valve normally closing the neck of the bottle and the stem holding the nipple separated from 10 the bottle sufficiently to form an air vent.

In testimony whereof, I have signed my name to this specification.

HARRY ANDREW SELLERS.
